UNITED STATES PATENT OFFICE.

JOHN DEMAREST, OF BINGHAMTON, NEW YORK.

GRATE.

SPECIFICATION forming part of Letters Patent No. 778,118, dated December 20, 1904.

Application filed February 6, 1904. Serial No. 192,261.

To all whom it may concern:

Be it known that I, JOHN DEMAREST, a citizen of the United States, and a resident of Binghamton, in the county of Broome and State of New York, have invented an Improvement in Grates, of which the following description, in connection with the accompanying drawings, is a specification, like letters on the drawings representing like parts.

10 My invention consists in improvements in grates intended particularly, though not exclusively, for cooking stoves or ranges. When the latter are supplied with two or more rocking grate members, it is customary 15 to interconnect them, as by gears, so that the shaking or reciprocation of the one will result simultaneously in a similar but reverse shaking or reciprocation of the other. It often happens, however, that the necessity for 20 shaking is confined to one grate member—as, for example, when the fire burns brightly on the oven side of the fire-pot, but has become clogged at the opposite side, and that grate member alone should be shaken or should be 25 shaken more violently than the other in order to properly clear the fire to produce uniform combustion.

My invention provides means for actuating or agitating certain portions of the grate area 30 independently of the remaining portion thereof and, further, provides for preventing the movement of the disengaged grate member or members corresponding to the unagitated area during the agitation of the remaining grate 35 member or members to preclude the possibility of dumping the fire or any portion thereof.

My invention will be best understood by 40 reference to the following description, taken in connection with the accompanying drawings, illustrating one specific embodiment thereof, while its scope will be more particularly pointed out in the appended claims.

In the drawings, Figure 1 is a plan view of 45 my invention as applied to an ordinary form of cooking-stove grate. Fig. 2 is an end elevation of the same, showing the locking device in an intermediate position. Fig. 3 is a side elevation of the same, partly in section, 50 looking from the right, Fig. 2. Fig. 4 is a

view similar to Fig. 2 with the shaker in position upon the left-hand member. Fig. 5 is a view similar to Fig. 4 with the shaker engaging the other grate member.

In the drawings, *a* and *b* are the two grate 55 members of an ordinary form of rocking grate, the same being pivotally mounted at their front and rear ends in suitable portions of the stove-walls in such manner as to permit of the necessary rocking movement to 60 give the desired agitation to the contents of the fire-pot. At their front ends the grate members are provided, respectively, with exteriorly-arranged engaging portions *c* and *d*, 65 projecting through the front stove-wall *e* and adapted to be engaged by any suitable form of shaker or other agitating or operating device. The engaging portions *c* and *d* are herein shown as formed by squaring the pivoted ends of their respective grate members, 70 as is usual, with the ordinary single shaking-shank. By this means either grate member may be shaken or agitated independently of the other and with reference to the character of the fire immediately above it.

Between the two projecting shaking portions *c* and *d* there is provided suitable means for locking or stopping the movement of either grate member during the agitation or operation of the remaining one. In the embodiment of my invention herein illustrated this comprises a locking member *f*, 80 slideable within suitable guideways *g*, the said locking member being recessed at each side to provide locking-walls adapted to engage the 85 squared sides of either one or both of the two engaging portions *c* and *d*. The locking member *f* when in the intermediate position shown in Fig. 2, wherein the squared shanks *c* and *d* are held within corresponding locking-recesses, 90 effectually prevents the movement of either of the said shanks. When it is desired to rock one of the grate-bars—as, for example, *b*—the slideable locking member *f* is caused to be moved to the right as viewed 95 in Fig. 2 to assume the position shown in Fig. 4, where the slide is shown as wholly withdrawn from engagement with the shank *d* and confining within its appropriate locking-recess the shank *c* only, which latter is 100

therefore locked in fixed position during the rocking of the grate-bar *b*, which may now be effected by means of the shaker or operating member *h*.

5 If it be desired similarly to shake the grate-bar *a*, the slideable locking member *f* is moved to the extreme left to the position shown in Fig. 5, where the conditions are reversed, the shank *d* being fixedly held in position and the shank *c* being engaged by the shaker ready for its agitation.

In order that the freedom or release of the grate member engaged by the shaker and the locking of the remaining grate member may be insured, the slideable locking member *f* is provided with a projecting portion *i* intermediate the two shanks. The space between the two shanks is so occupied by the projecting portion *i* that the shaker cannot be applied to either shank excepting that the slide *f*, with the portion *i*, be moved to its extreme limit in the opposite direction, which insures the release of the shank previously engaged and the locking of the other shank. Thus in Figs. 4 and 5 it will be observed that space enough only has been provided between the engaged shank and the opposing wall of the projecting portion *i* to permit the application of the shaker to the shank.

30 In order that the movement of the shaker toward its position of engagement with either shank may effect the necessary movement of the locking means, I have shown the walls of the projecting portion *i* next adjacent the shanks *c* and *d* beveled and the inner edge of the shaker provided also with a corresponding bevel adapted to engage the bevel upon the portion *i* in order that the latter, together with the slide, may be forced laterally in one direction or the other, if it be not already in appropriate position, as the shaker is forced upon the shank.

It will be obvious that my invention is susceptible of extensive modification both in form and arrangement of parts from the specific embodiment, which is submitted for illustrative purposes only, and that the same may be widely varied without departing from the spirit thereof.

50 I claim—

1. A rocking grate having two rocking grate members provided each with an exteriorly-arranged portion adapted to be engaged by an operating member, said engaging portions being of non-circular cross-section, a slideable locking device between said engaging portions and provided with locking-walls extended on each side to engage the sides of either of said engaging portions and lock the same in fixed position, and means upon said slideable locking device to prevent the application of said operating member to the engaged portion of one grate member except the other grate member be locked.

65 2. A rocking grate having two rocking

grate members provided each with an exteriorly-arranged portion adapted to be engaged by an operating member, said engaging portions being of non-circular cross-section, and a slideable locking device between said engaging portions and provided with locking-walls extended on each side to engage the sides of either of said engaging portions and lock the same in fixed position according to the position of said locking device. 75

3. A rocking grate having two rocking grate members provided each with an exteriorly-arranged engaging portion adapted to be engaged by an operating member, and a movable locking device between said engaging portions adapted also to be engaged by said operating member on its engagement with either of said portions to lock the remaining portion in fixed position. 80

4. A rocking grate having a plurality of 85 rocking grate members provided each with an exteriorly-arranged engaging portion, an operating member adapted to engage with either of said portions, and means acting during the operation of one of said grate members for insuring the locking of another of said members. 90

5. A rocking grate having a plurality of 95 rocking grate members and provided each with an exteriorly-arranged portion, an operating member adapted to engage with either of said portions and locking means controlled by said operating member to insure the release of one of said grate members on engagement of said operating member therewith and the locking of a remaining grate member. 100

6. A rocking grate having a plurality of 105 rocking grate members having each an exteriorly-arranged portion adapted to be engaged by an operating member, and locking means 110 between said exteriorly-arranged portions for enforcing the locking of one of said grate members in fixed position during the agitation of a remaining member by said operating member.

7. A rocking grate provided with a plurality of rocking grate members and means interposed between said grate members compulsorily locking one of said members prior to the agitation of the other. 115

8. A rocking grate provided with a plurality of grate members, exteriorly-arranged engaging portions on said grate members, an operating member adapted for individual engagement with said engaging portions to cause 120 agitation thereof, and a locking device to enforce the locking of a grate member during agitation of a remaining member.

9. A grate having a plurality of agitable grate members, means for operating the same, and means for compulsorily locking one of the grate members during the agitation of the remaining member. 125

10. A grate member having a plurality of independently-movable grate members, and 130 1

locking means for said grate members requiring the locked condition of one member as a condition precedent to the release of the remaining member.

5 11. A grate having a plurality of separately-agitable grate members, combined with locking means for compelling the locking of one of said members in fixed position during agitation of another.

10 12. A grate having a grate area formed by a plurality of agitable grate members, and means to effect separate agitation of different portions of the grate area, and means whereby the agitation of one grate-area portion is possible only when another portion is quiet.

15 13. A grate having a plurality of movable grate members, an operating member, said grate members having means to permit of separate engagement between said operating member and any particular grate member for effecting the operation of said member, and means permitting the operation of a member by said operating member and preventing the

movement of any grate member not engaged by the operating member.

25 14. A grate having a plurality of movable grate members, an operating member, means to permit of separate engagement between said operating member and different grate members, and means acting as a condition to the engagement of said operating member with one of said grate members to prevent the movement of another of said members.

30 15. A grate having a plurality of agitable grate members, means to operate any selected grate member, means to prevent the operation of the remainder rendered operative upon and by the application of the operating means to the selected grate member.

35 In testimony whereof I have signed my name to this specification in the presence of two subscribing witnesses.

JOHN DEMAREST.
